Primary Examiner — Steven J Czyz

(57) **CLAIM**

The ornamental design for a 5 gallon water bottle holder, as shown and described.

DESCRIPTION

FIG. 1 is a top perspective view of a 5 gallon water bottle holder, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the 5 gallon water bottle holder, shown with additional racks stacked on top;

FIG. 10 is another perspective view of the 5 gallon water bottle holder, shown with additional racks stacked on top;

FIG. 11 is a perspective view of the 5 gallon water bottle holder, shown with an additional rack and shelf stacked on top; and,

FIG. 12 is a perspective view of the 5 gallon water bottle holder, shown with additional racks and shelf stacked on top. The broken lines in the drawings illustrate the portions of the 5 gallon water bottle holder, which form no part of the claimed design.
